UNITED STATES PATENT OFFICE.

DANIEL T. FINKBEINER, OF FREEPORT, PENNSYLVANIA.

RAIL-JOINT.

1,184,637.

Specification of Letters Patent. Patented May 23, 1916.

Application filed July 30, 1915. Serial No. 42,723.

To all whom it may concern:

Be it known that I, DANIEL T. FINK-
BEINER, a citizen of the United States, re-
siding at Freeport, in the county of Arm-
strong and State of Pennsylvania, have in-
5 vented new and useful Improvements in
Rail-Joints, of which the following is a
specification.

This invention is an improvement of the suspended type of rail joint in which a splice bar is employed, provided with a bridge piece arranged to bridge the space between the rail ends.

One of the objects of the invention is to provide a continuous rail by bridging the space between the rail ends, in such manner as to eliminate as far as practicable the disastrous blow dealt by the rolling stock upon the rail heads at the joint, resulting in increased efficiency in train movements and the prolonging of the life of the joint material.

A further object is to provide a rail joint of this type which possesses no lap joint features.

25 A further object is to provide ample space for the inclining of the transverse bolts, due to expansion, contraction, and creeping of the rail.

A further object is to provide a rail joint free of parts that protrude beyond the rail, and which might trip track walkers, and others who are compelled to walk along the railroad track.

A further object is to provide a rail joint
35 so constructed that the wave motion in the
rails is permitted to pass through the joint
with the least harmful results, and with the
parts so arranged that no part of the bridge
portion will wear away excepting the top
40 thereof, which wears uniformly with the
rail.

A further object is to provide a joint which will not rob the rail head, at the joint, of the strength which lies in the rail web, and which will permit the rails to wear away to the point where safety naturally demands a renewal of the same, without giving rise to the liability of derailment, due to worn or broken rail ends.

50 A further object is to provide an improved

splice bar having a bridge piece, and means for resisting the stresses tending to shear the bridge piece from the body of the splice bar, and for directing said stresses through the body of the bar to the flange of the rail. 55

The invention will be hereinafter fully set forth and particularly pointed out in the claims.

In the accompanying drawing:—Figure 1 is a view in plan illustrating the bridge splice. Fig. 2 is a side elevation thereof. Fig. 3 is a vertical sectional view of the splice bar at its widest part, *i. e.*, midway between the ends. Fig. 4 is a vertical sectional view of the joint. Fig. 5 is a horizontal sectional view of one half of the joint and Fig. 6 is a top plan view of the other half of the joint. Fig. 7 is a side elevation of the joint. 60 65

Referring to the drawings, the splice bar 70 comprises a body 10 provided at its lower edge with a laterally extended flange 11 provided with a depending foot 12. The upper edge of the splice bar is provided with an upwardly extended bridge piece 13, which is of approximately triangular shape in plan view, and the inner edge of the bridge portion being provided with a pyramidal portion 13^a which overhangs the main body of 75 said splice bar. The overhanging triangular portion forms a bridge adapted to engage recesses 15 formed by beveling the outer faces of the treads of the rails 16, at their meeting ends, said rails being provided with the usual web 17 and flange 18. Each 80 of the bevels employed to form the recesses 15, extends from the outer face of the tread of the rail to a point in line with the outer face of the web of the rail (see Figs. 5 and 6), thereby providing a comparatively shallow recess and avoiding a lap-joint between 85 90

the bridge piece 13 and the top of the web as would be the case if the recess were deep enough to extend across any portion of said web. The joint is also reinforced by a splice 95 bar 19 located on the inner side of the rail, the upper edge of said bar being thickened as indicated at 20 to provide a head supporting the rail head, the lower edge of said splice bar being provided with a lateral 100

flange 21 and a depending foot 22. The outer portion of the rail head, beyond the bridge member 13, is supported by the overhanging upper edge of the splice bar 10, said overhanging portion being approximately in the same vertical plane as the inner extremity of said bridge piece, as shown in Figs. 3 and 4. It will be observed that the body portions of the splice bars 10 and 19 are spaced from the rail web 17.

In operation, the stress of the load passing over the rails, tends to force the inner edge of the bridge piece downwardly and therefore to force the body 10 outwardly, which action tends to shear the bridge piece from the main body 10. In order to resist this shearing action I provide the pyramidal portion 13^a, which gives ample support to that portion of the bridge piece which overhangs the main body of the splice bar, and also provides a means by which the stress imposed upon the overhanging feature may be directly transmitted to the main body of the splice, and hence eliminate the liability of shearing or fracturing the overhanging portion of the bridge. The pyramidal portion 13^a also performs another important function, namely, in tightening the bolts which are employed to unite the parts, there is, owing to the space between the splice bar and the web of the rail, a tendency to move the body of the splice bar inwardly to such an extent as to shear off the bridge piece from splice bar. The pyramidal portion 13^a prevents this action by serving as an abutment to contact with the rail web and limit the inward movement of the splice bar.

The splice bars are provided with holes for the passage of the securing bolts, as illustrated, each splice bar being provided with alternately arranged elliptical holes 25 and circular holes 26, the circular holes of one bar being arranged opposite the elliptical holes of the other bar. The circular holes 26 of the bar 10 are provided with elliptical enlargements at their inner ends, to allow ample room for the inclining of the bolts. Any preferred type of bolt may be employed, that illustrated comprising the usual shank 28 having a head 19 and a threaded portion 30 upon which works a securing nut 31, a nut lock 32 of any preferred type being interposed between the nut and the splice bar. The bolts are alternately extended in opposite directions, the headed end of the bolt being passed through the elliptical openings 25. The flanges 11 and 21 of the splice bars rest upon the opposite extensions of the flange 18 of the rail, and are secured in position by spikes or similar devices extending through the openings 33. The tie plates and cross ties are represented by 34 and 35 respectively.

Having thus explained the nature of my

invention and described an operative manner 65 of constructing and using the same, although without attempting to set forth all of the forms in which it may be made, or all of the forms of its use, what I claim is:—

1. As an improvement in rail joints, the 70 combination with two meeting rails having the outer faces of their treads at their meeting ends, provided with complemental converging beveled portions coöperating to form a recess, each beveled portion extending 75 from the outer face of the tread of the rail to a point approximately in line with the outer face of the web of the rail, a splice bar having its upper edge provided with a bridge member overhanging the inner face 80 of said bar and filling said recess, the under side of the inner edge of said splice bar being provided with a pyramidal supporting extension below the plane of the bridge member and abutting against the web of 85 the rail, a second splice bar supporting the inner sides of the meeting rails, and means for uniting said splice bars and said rails.

2. As an improvement in rail joints, the 90 combination with two meeting rails having the outer faces of their treads at their meeting ends, provided with complemental converging beveled portions coöperating to form a recess, each beveled portion extending 95 from the outer face of the tread of the rail to a point approximately in line with the outer face of the web of the rail, a splice bar, the body of which is spaced from the webs of the rails, with its upper edge in engagement with the under side of said treads, said 100 upper edge being provided with a bridge member extending above the plane of said upper edge and overhanging the inner face of said splice bar and filling said recess, the under side of the inner edge of said splice 105 bar being provided with a pyramidal supporting extension below the plane of the bridge member and abutting against the web of the rail, a second splice bar supporting the inner sides of the meeting rails, and 110 means for uniting said splice bars and said rails.

3. As an improvement in rail joints, the 115 combination with two meeting rails having the outer faces of their treads, at their meeting ends, provided with complemental beveled portions coöperating to form a recess, each beveled portion extending from the outer face of the tread of the rail to a point approximately in line with the outer 120 face of the web of the rail, a splice bar engaging said treads and having its upper edge provided with an upwardly projected bridge member, having a portion overhanging the inner face of said plate and filling said recess, a second splice bar supporting the inner sides of the meeting rails, said splice bars 125 being provided with alternately arranged

circular and elliptical openings, the circular openings of one bar being arranged opposite the elliptical openings of the other bar, and bolts passed through said openings, the inner 5 ends of the circular openings of the first mentioned splice bar being provided with elliptical enlargements.

In testimony whereof I have hereunto set my hand in presence of two subscribing witnesses.

DANIEL T. FINKBEINER.
